US0D1018894S

(12) **United States Design Patent** (10) **Patent No.:** **US D1,018,894 S**
(45) **Date of Patent:** **** Mar. 19, 2024**

(54) **PROTECTIVE HOLDER FOR MEDICAL INSTRUMENTS**

(71) Applicant: **Zhejiang Orient Gene Biotech Co., Ltd**, Zhejiang (CN)

(72) Inventor: **Jianqiu Fang**, Zhejiang (CN)

(73) Assignee: **ZHEJIANG ORIENT GENE BIOTECH CO., LTD**, Zhejiang (CN)

(**) Term: **15 Years**

(21) Appl. No.: **29/810,179**

(22) Filed: **Oct. 1, 2021**

(30) **Foreign Application Priority Data**

Jul. 27, 2021 (CN) 202130480665.8

(51) **LOC (14) Cl.** **24-02**

(52) **U.S. Cl.**

USPC **D24/223; D24/227**

(57) **CLAIM**

The ornamental design for a protective holder for medical instruments, as shown and described.

DESCRIPTION

FIG. 1 is a top view of a protective holder for medical instruments showing my new design;

FIG. 2 is a bottom view thereof;

FIG. 3 is a left side view thereof;

FIG. 4 is a right side view thereof;

FIG. 5 is a front elevational view thereof;

FIG. 6 is a rear elevational view thereof;

FIG. 7 is a top perspective view thereof;

FIG. 8 is a bottom perspective view thereof; and,

FIG. 9 is a perspective view of the protective holder for medical instruments in use.
The broken lines in the drawings depict environmental subject matter and form no part of the claimed design.
